United States Patent Office

Des. 179,531
Patented Jan. 8, 1957

179,531

KNIFE

Paul Voss, Solingen-Wald, Germany, assignor to Carl
Prinz A. G. für Metallwaren, Solingen-Wald, Germany

Application May 4, 1955, Serial No. 35,811

Term of patent 7 years

(Cl. D22—3)

Fig. 1 is an edge view of a knife showing my new design;

Fig. 2 is a plan view thereof;

Figs. 3, 4 and 5 respectively are enlarged sections on the lines 3—3, 4—4 and 5—5 of Fig. 2.

The essential feature of the knife design resides in the portion shown in full lines on the drawing.

I claim:

The ornamental design for a knife, as shown and described.
